UNITED STATES PATENT OFFICE.

HARRY C. McCARTY, OF WILLIAMSPORT, PENNSYLVANIA.

DUST-GUARD FOR JOURNAL-BOXES.

1,267,569.

Specification of Letters Patent. Patented May 28, 1918.

Application filed August 29, 1917. Serial No. 188,698.

To all whom it may concern:

Be it known that I, HARRY C. McCARTY, a citizen of the United States, residing in Williamsport, in the county of Lycoming and State of Pennsylvania, have invented certain new and useful Improvements in Dust-Guards for Journal-Boxes, of which the following is a specification.

This invention relates to journal-boxes, 10 and especially to journal-boxes used upon railroads, street railway or mine or like cars, in which the wheels are fixed to the axles; and axles revoluble in journal-boxes. The present invention comprises a new and improved form of dust-guard for encircling the axle for preventing the entrance of dust or dirt, at the same time assisting, by capillary-attraction, the feeding of oil or other lubricant to the journal.

20 This invention is a modification of, and an improvement on the devices shown, described and claimed in my two Letters Patent for a dust-guard, No. 711,641, granted October 21, 1902; and Letters Patent No. 743,653, for a journal-box, granted November 10, 1903; and my application, Serial No. 150,917, filed February 26, 1917.

I have found by experience that a very efficient and durable dust-guard and a very efficient means of lubrication is formed by having such guard stiffened at its outer edges by means of folded pieces of fabric; and that its insertion and removal are facilitated by such stiffening; and I have also found that such a dust-guard is easily placed in position in the pocket provided in the journal-box for receiving such dust-guard; and that the guard is snugly received in said pocket.

30 40 My said invention may be very cheaply constructed and is fully shown, described and claimed in the following specification, of which the accompanying drawing forms a part: wherein similar letters and numerals of reference designate like or equivalent parts throughout the several views and in which:

Figure 1 is a view in longitudinal central vertical section of my improved journal-box and dust-guard, with the car-axle and dust-guard in position;

50 55 Fig. 2 is a view of such dust-guard and axle in vertical section, taken on the line 2-2 of Fig. 1, looking toward the right in the direction of the arrow;

Fig. 3 is a view in detail in perspective

and also central vertical section on the line 3-3 of Fig. 2;

Fig. 4 is a view in detail of a portion of the axle, with the contacting portion of the dust-guard shown in section mounted thereon.

Referring more particularly to the drawing:

A designates a car journal-box which may be that shown, or may be the Master Car Builders' journal-box having the front opening, for introducing lubricating-material, closed in the well-known manner by journal-box lid B, pivoted at 10, and provided with the spring 11, for maintaining the same in the open position for cleaning, or introducing new lubricant. Such journal-box is, of course, provided with suitable means for securing the same rigidly to the truck-frame; but as this forms no part of my invention, I have not deemed it essential to show or indicate this part of the construction.

At the inner end of such journal-box, is formed the pocket 12 open at the top, having the inner-wall 13, and the outer-wall 14; and the side-walls 15 and bottom 16; which pocket is usually of the rectangular form clearly indicated in Fig. 1.

C. indicates the axle and C', the journal-bearing surface, and upon the same is superposed in the well-known manner, the usual bearing-plate D.

My improved dust-guard, used with this particular form of journal-box, comprises a rectangular dust-guard body G, usually and preferably formed of two superposed sheets of suitable flexible woven wick-like material, such as cotton-duck, etc., which will capillary feed the lubricating oil from the bottom of the journal-box, to the center of said guard G, and to the axle.

As shown in the drawing, such dust-guard G, is formed of three or more plies of canvas or other suitable wick-like material, having the central opening 17, prevented from spreading adjacent to such opening by the circular line of stitches 18, surrounding such opening; and secured to one face of the sides and bottom and top of such one or more ply flexible fabric dust-guard, is an outer rectangular stiffening frame 19 composed of suitable wick-like fabric, for instance, the same fabric as the main portion of the dust-guard. This frame 19 is formed by folding the fabric upon itself, as at 20, whereby the frame comprises

four plies as shown in Figs. 1, 3, and 4. The plies of the frame are stitched together by the lines of stitches 22 and then the whole is stitched to the body of the dust-guard by lines of stitches 24 passing entirely through the one or more plies of the dust-guard body and two or more plies of the frame.

10 The main body portion of the dust-guard G is strengthened by the insertion, between the plies thereof, of a strengthening ply 23 extending to the outer edge of the dust-guard and terminating at its inner edge near the line of stitches 18.

15 When the guard is in position the frame forms a somewhat yielding combined packing and stiffening which prevents entrance of dust through the open top of the pocket.

In assembling, the dust-guard G. is placed 20 in position in the dust-guard pocket 12, by slipping the same in from the top. When in such position the central orifice 17 of the dust-guard G, being slightly smaller in diameter than the inserted axle C, the one 25 or more plies thereof, will be slightly spread apart at the bottom as clearly indicated at 26 of Figs. 1 and 4; whereby the ingress of dust and dirt is prevented and the feeding of the oil contained in the bottom 27, of 30 the journal-box A will be more liberally distributed to the axle.

It is evident that many changes and modifications in the construction, combination and arrangement of the several parts of my 35 device herein shown, described and claimed, may be made, without departing from the scope of my invention, but I do not intend to limit myself to the exact construction shown and described.

40 I claim as my invention:

1. A dust guard composed substantially entirely of flexible material, said dust guard being thicker at the marginal portion than at the intra-marginal portions.

45 2. A dust guard composed substantially entirely of flexible material, said dust guard being stiffer at the marginal portion than at the intra-marginal portions.

3. A dust guard composed substantially 50 entirely of flexible material, said dust guard being thicker and stiffer at the marginal portion than at the intra-marginal portions.

4. A dust guard having a flexible marginal portion thicker than the intra-marginal 55 portion of the guard.

5. A dust guard having a wick-like marginal portion thicker and stiffer than the intra-marginal portion.

6. A dust guard having a wick-like marginal portion thicker than the intra-marginal 60 portion.

7. A dust guard having a wick-like marginal portion stiffer than the intra-marginal portion.

65 8. In a dust guard, the combination of a

body portion; a frame disposed on said body portion and comprising a plurality of thicknesses in addition to the body portion; and means securing the frame to the body portion.

70 9. In a dust guard, the combination of a flexible body portion comprising a plurality of thicknesses of wick-like material; a flexible frame of wick-like material disposed on the marginal portions of said body portion and comprising a plurality of thicknesses in addition to the body portion; and stitches securing the frame to the body portion.

75 10. In a dust guard, the combination of a body portion; a frame; and stitches securing the frame to the body portion, said dust guard being thicker and stiffer at the marginal portion than at the intra-marginal portions.

80 11. In a dust guard, the combination of a flexible body portion comprising a plurality of thicknesses of wick-like material; a flexible frame of wick-like material disposed on the marginal portions of said body portion and comprising a plurality of thicknesses in addition to the body portion; and stitches securing the frame to the body portion, said dust guard being thicker and stiffer at the marginal portion than at the intra-marginal portions.

85 12. In a dust-guard, the combination of a body portion; a frame disposed at the edges of said body portion and composed of a plurality of folds of flexible material; and stitches securing the frame to the body portion.

90 13. In a dust-guard, the combination of a body portion; and a frame disposed at the edges of said body portion and composed of a plurality of folds of wick-like flexible fabric material.

95 14. In a dust-guard, the combination of a body portion; a frame disposed at the edges of said body portion and composed of a plurality of folds of wick-like flexible fabric material; and stitches securing the frame to the body portion.

100 15. In a dust-guard, the combination of a body portion; and a frame disposed at the edges of said body portion and composed of a plurality of folds of wick-like flexible fabric material forming a plurality of plies.

115 16. In a dust-guard, the combination of a body portion; a frame disposed at the edges of said body portion and composed of a plurality of folds of wick-like flexible fabric material forming a plurality of plies; and stitches passing through said plies and securing the frame to the body portion.

120 17. In a dust-guard, the combination of a body portion; a frame disposed at the edges of said body portion and composed of a plurality of folds of wick-like flexible fabric material forming a plurality of plies, and lines of stitches securing said plies together.

18. In a dust-guard, the combination of a body portion; a stiffening and packing frame disposed at the edges of said body portion and composed of a plurality of folds of wick-like flexible fabric material forming a plurality of plies; lines of stitches securing said plies together; and stitches passing through said plies and securing the frame to the body portion.
- 10 19. In a dust-guard, the combination of a body portion comprising a plurality of plies of wick-like flexible fabric material; a stiffening and packing frame disposed at the edges of said body portion and composed of 15 a plurality of folds of wick-like flexible fabric material forming a plurality of plies; lines of stitches securing said plies together; and stitches passing through said plies and securing the frame to the body portion.
- 20 20. A dust-guard comprising a plurality

of plies of superposed flexible material provided with a central opening; and strips of flexible material folded upon each other and stitched to the outer edges of the guard for strengthening the same.

25

21. A dust-guard for revolving axles, shafts and the like, comprising a plurality of superposed plies of wick-like canvas provided with an opening to receive the axle; lines of stitches adjacent to said opening 30 for holding the inside edges of the plies together; strips of similar material composed of several thicknesses thereof folded upon each other and stitched together; and stitches securing said strips to the outside edges of 35 the dust-guard for strengthening the same.
